UNITED STATES PATENT OFFICE.

SAMUEL BEVINGTON, OF PHILADELPHIA, PENNSYLVANIA.

PORTABLE FURNACE FOR BURNING THE ENAMELING ON PORCELAIN, &c.

SPECIFICATION forming part of Letters Patent No. 251,821, dated January 3, 1882.

Application filed May 17, 1881. (No model.)

To all whom it may concern:

Be it known that I, SAMUEL BEVINGTON, a subject of the Queen of Great Britain, residing at Philadelphia, in the county of Philadelphia and State of Pennsylvania, have invented certain new and useful Improvements in Portable Furnaces for Burning the Enameling, &c., on Porcelain and Similar Ware, of which the following is a specification, reference being had to the accompanying drawings, wherein—

Figure 1 is a transverse vertical section of a furnace embodying my invention. Fig. 2 is a front elevation of the same. Fig. 3 is a like view with the exterior metallic doors and interior front section of the wall of the furnace removed, exposing to view the front of the oven. Fig. 4 is a like view with the metallic doors only removed. Fig. 5 is a longitudinal vertical section of my improved furnace. Figs. 6 and 7 are horizontal sections on the lines 1 1 and 2 2, Fig. 5, respectively.

My invention relates to portable furnaces for burning the enameling on porcelain, glass, earthenware, jewelry, and other like articles, and has for its object to so construct the furnace that such enameling will be burned on said articles free from sulphur and mildew, and more perfectly and in a superior manner than has heretofore been accomplished by the use of furnaces as now constructed and operated, my furnace being so constructed and manipulated that the heat from the same causes such enamel to become incorporated into or integral with the article upon which it is placed; hence said 35 enameling cannot be washed out or otherwise destroyed.

My invention has for its further object to so construct the furnace that after the enamel has been burned on the porcelain-ware, &c., the heat accumulating in the oven during such operation will gradually but rapidly be conducted or caused to pass out of the oven without opening any part of the same, so that the various articles placed therein will gradually cool in a very short time, to prevent any crackling of the enamel thereon, and whereby the said articles may the sooner be removed from the oven and replaced by a fresh charge or set, thereby providing for frequent "firing up" of the furnace in a given time, to increase the capacity of the furnace and cheapen the cost of production.

My invention has for its still further object to dispense with the expensive and cumbersome brick-work or masonry heretofore considered essential in the above class of furnaces.

To the accomplishment of such advantages my invention consists in the novel combination, arrangement, and construction of parts, having reference particularly to the following points: 55 to a furnace having a heating-chamber in which is a division-wall or partition for separating or dividing the heat coming from the furnace, so as to cause portions of the same to ascend on and around all sides of the oven; to the provision of an exterior tapering or conical furnace-wall and tapering flues between said wall and the inclosed oven; to the provision of said conical furnace-wall formed with exterior ribs or having its outer surface corrugated or fluted, 60 upon the ridges of which rest an inclosing metallic casing or sheath; to an oven having a 65 semicircular top, one or more peep-holes extending therefrom to the exterior of the furnace, the ends of which are covered with a sheet 70 of mica or other suitable material, and a tapering tube having communication with the external air for conducting out of the oven the moisture, &c., arising from the drying of the enamel, and, further, for allowing the heat 75 accumulating in said oven during the burning-on operation to be gradually but quickly conducted therefrom.

Referring to the accompanying drawings, A represents a cast-iron foundation or base, upon 80 which is built the fire place or box B, oblong in shape, as shown, and provided with a grate, b, and ash-pit b'.

C is the exterior furnace-wall, resting on said base A, made in sections, the edges of which 85 are rabbeted, so that when placed in position said sections will interlock and retain their location without the aid of mortar or other cement. Said sections, as well as those of which the fire-place B is constructed and those 90 to be hereinafter described, are all made of refractory clay, having their edges so formed as to interlock the said sections together so as to form a furnace and an oven, which are held together without the aid of cement or equivalent 95 substance. The exterior wall, C, is of a greater width at its bottom than at the top, whereby, when the oven D is placed within the same, as shown, the space between the said oven and

wall will be tapering in outline, with the narrowest part at the top of the oven. Said space is divided on three sides by vertical partitions $c\ c$ to form a series of tapering flues, $d\ d$, said partitions being continued over the semicircular top of the oven, as shown at $c'\ c'$, and the latter, being surmounted by a cap, E, resting on said partitions $c'\ c'$, forms the upper side or cover for the top flues, $d'\ d'$, all of which terminate in the flue e of cap E and pass out through the tapering opening e' in said cap to the smoke-stack. (Not shown in the drawings.)

The oven D is held supported in position by projections $c^3\ c^3$, formed on the partitions $c\ c$, as shown.

F is a tube passing out of the top of the oven D, and gradually tapers as it passes therefrom and through the wall C of the furnace, its end f having a plug or stopple, f'.

G G are sight or peep hole pipes extending from the front door or wall, d^2 , of the oven, and through the removable section C' of wall C. Said peep-holes are covered with a sheet of mica, which, if desired, may be held in place by a brass cap or other suitable device. The outer surface of the wall C is corrugated, fluted, or formed with ridges $c^2\ c^2$, against which impinges or rests a metallic sheath, H, so as to form between said wall and sheath a series of vertical openings, h h, said sheath and furnace being surmounted by a cap, I, to retain all of said parts in a fixed position.

Back of the fire-place B is a heat-chamber, K, provided with a wall k, which divides the heat emanating from the fire-box and causes parts of the same to pass up all of the flues $d\ d$ surrounding the oven, the bottom k' of said chamber having formed therein an opening, k^2 , the end k^3 of which terminates in the ash-pit b', and its remaining end, k^4 , communicating with the external air at the opposite side of the furnace.

L L are folding metallic doors, hinged at ll to the cover or sheath H, and serve to protect the movable section C' of wall C in the same manner as the sheath H does for the latter, as hereinafter fully described.

n n' are the upper and lower furnace-doors, hinged at $n^2\ n^2$, as shown, the door n being attached to a chain, o, passing over a pulley, o', in beam o², secured to cap I by being slipped through loop i secured thereto, said chain having at its opposite end a counterbalancing-weight, o³, whereby, when the weight is raised or lowered, the door n is lifted or moved downwardly from and to the fire-place B to open or close the draft to the furnace. The door n', when down, acts as a fender, and when drawn up and so secured by attaching the end of its chain n⁴ to chain o it shuts off the draft through the ash-pit.

The operation is as follows: The articles on which the enamel is to be burned, being properly prepared, are placed upon the perforated shelves d⁵ in the oven D, its door d² closed, and held so by button d⁴. The section C' is now

adjusted in position and the metallic doors L closed. The fire is now lighted in the fire-place B, its doors n n' adjusted to regulate the draft required. The heat from fire-box B passes into chamber K, and is divided by the wall k, the outer edge of which is made prow-shape, as shown, for that purpose, and a portion of such heat is caused to pass up each one of the flues d d. The latter being tapering, a suction is caused thereby in said flues, and the draft thus produced soon causes the fire-box B to emit an intense heat, which being conducted or radiated through the refractory walls of the oven D, the articles therein are soon raised to a white heat, and the enamel thereon, being subjected to the same heat, coalesces or becomes incorporated with the material of such articles, and is set or so burned on the same that it cannot be washed out or otherwise destroyed. The heat, as it passes up the flues d, passes out through tapering opening e'. The latter being so formed acts to also suck or rapidly draw the heat through flues d' d' and e. The provision for sucking or drawing the heat, as described, is to provide a draft in the flues surrounding the oven, to enable the fire in the box or place B to the sooner give off the intense white heat necessary for such burning-on operation and to prevent the heat remaining in such passages to decrease the draft and to smother the furnace-fire. When the fire is first started the plug f' is removed from the pipe F to allow the escape of the moisture from the oven D emanating from the enamel and the articles therein. The provision for conducting away such moisture and other vapors arising from the drying of the enamel allows the same to be burned in the articles on which they are placed free from sulphur and mildew. Consequently the colors of such burned-on enamel are of a brighter hue and brilliancy than is the case where said moisture is retained in the oven during the entire operation of burning on said enamel, as has heretofore been done. As soon as the moisture passes off from the oven said plug is replaced, and there being now no outlet for the escape of the heat from the oven the articles therein soon become intensely heated, the progress of which may be ascertained by looking through the peep-holes G G from time to time. When the operation is completed the furnace-doors n n' are closed and the fire in the box B smothered. The plug f' is now again removed from pipe F, and the accumulated heat in oven D passes or is sucked therethrough gradually but rapidly, thereby reducing the temperature of the articles in the oven, but doing so evenly and gradually so that the enamel thereon will not fissure or crack. When sufficiently cooled the doors L L are opened, the section C' and door d² removed, the oven emptied of its contents, which are replaced by a fresh charge, and the operation repeated, which may be done as often as the demands or requirements of the business necessitate. Such operation being performed in two (2) or thereabout

hours, it will be seen that the furnace is a very efficient one, there being no brick-work or masonry about it, being built wholly of refractory clay and iron, the latter forming a sheath to 5 keep the heat in the furnace-wall proper by reason of the cold-air passages h between said wall and sheath.

I have shown the furnace as being circular in shape; but it is evident that the same may 10 be made oblong in form or of any suitable configuration without departing from the spirit of my invention.

What I claim as my invention is—

1. A furnace for burning enameling on porcelain, &c., consisting of a fire-box, a conical wall 15 the exterior surface of which is fluted or corrugated, a surrounding metallic sheath, an interior oven, between which and the fluted wall are tapering flues terminating in a contracted 20 or conical exit-opening, substantially as shown and described.

2. A furnace for burning enameling on porcelain, &c., consisting of a fire-box, exterior fluted 25 wall, and metallic covering, and an interior oven provided with a tapering exit-pipe and peep-holes, and having between said oven and fluted wall a series of tapering heat-flues, substantially as described.

3. A furnace for burning enamel on porcelain, 30 &c., consisting of a fire-box, a heat-chamber back of the same and below the oven, and provided with a division wall or partition, from said chamber arising a series of tapering flues sur-

rounding the oven, and an outer wall the exterior surface of which is corrugated or fluted and 35 surrounded by a metallic covering or sheath, substantially as shown and described.

4. The combination of fire-box A, heat-chamber K, wall C, corrugated exteriorly, the sheath H, oven D, having tapering pipe F, surrounded 40 with tapering flues d, substantially as shown and described.

5. The combination, with furnace B, having walls C, of oven D, provided with perforated shelves d⁵, tapering flue F, having stopple f', and peep-hole pipes G, substantially as 45 shown and described.

6. The combination, with furnace B, provided with doors n n' and attached chains o and n⁴, and counterpoise o³, of walls C C, having surrounding sheath H, provided with folding doors L L, substantially as shown and described.

7. In combination with furnace B, walls C C, and oven D, said parts being arranged in relation to each other to provide tapering flues 55 d d between said oven and walls, a heating-chamber, K, having partition k, the forward edge of which is beveled or made prow shape, substantially as shown and described.

In testimony that I claim the foregoing I 60 have hereunto set my hand this 21st day of February, A. D. 1881.

SAMUEL BEVINGTON.
